CLAIM

We claim the ornamental design for a wet/dry vacuum cleaner with handle, as shown and described.

DESCRIPTION

FIG. 1 is a front perspective view of a wet/dry vacuum cleaner with handle showing the new design.

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.

The details shown in broken lines form no part of the claimed design.

1 Claim, 7 Drawing Sheets
